UNITED STATES PATENT OFFICE

LESTER F. NENNIGER, OF CINCINNATI, OHIO, ASSIGNOR, BY MESNE ASSIGNMENTS, TO THE HEALD MACHINE COMPANY, OF WORCESTER, MASSACHUSETTS, A CORPORATION OF MASSACHUSETTS

GRINDING MACHINE

Application filed January 25, 1932. Serial No. 588,627.

This invention relates to improvements in grinding machines and especially to improvements in a mechanism for maintaining sizes of work pieces being ground.

Attempts have been made in the past to automatically control the size of work pieces while being operated on or ground. Difficulty has been experienced in the accurate proper performance of these mechanisms especially when employed with internal grinding machines and when attempting to control the size of the hole or bore being ground. This was caused by variations in the outside diameter of the work which was the determinator for the hole and its size. By the mechanism of this invention these difficulties have been overcome and the size of the hole or bore maintained regardless of the size of the outside circumference.

It is, therefore, one of the principal objects of the present invention to provide a mechanism which will control the size of the bore or hole in successive work pieces regardless of the sizes of the outside diameter.

Another object of the invention is the provision of a compensating mechanism operating and controlling the sizing mechanism for positioning same in accordance with the finished outside size of the work.

A further object of the invention is the provision of a mechanism as above set forth operating in an automatic manner in timed sequence with the automatic portions of the balance of the machine.

Other objects and advantages of the present invention should be readily apparent by reference to the following specification considered in conjunction with the accompanying drawings forming a part thereof and it is to be understood that any modifications may be made in the exact structural details there shown and described within the scope of the appended claims without departing from or exceeding the spirit of the invention.

In the drawings:

Figure 1 is a front elevation of a grinding machine embodying the improvements of this invention.

Figure 2 is a top plan view of the machine shown in Figure 1.

Figure 3 is a sectional view taken on line 3—3 of Figure 2.

Figure 4 is a fragmentary sectional view taken on line 4—4 of Figure 3.

Figure 5 is a sectional view taken on line 55 5—5 of Figure 2.

Figure 6 is a sectional view taken on line 6—6 of Figure 2.

Figure 7 is a sectional view taken on line 7—7 of Figure 5.

Figure 8 is a sectional view as seen substantially from line 8—8 of Figure 1.

Figure 9 is a sectional view taken in a plane parallel with but ahead of the structure shown in Figure 8.

Figure 10 is a sectional view taken on line 10—10 of Figure 8.

Figure 11 is a diagrammatic view illustrating the hydraulic and electrical circuits involved in the machine with which this invention is employed.

Throughout the several views, similar reference characters are employed to denote the same or similar parts.

This invention is particularly useful with automatic machines such as internal grinding machines. The invention has therefore been illustrated in conjunction with an internal grinding machine which is operated in accordance with centerless grinder principles. Accordingly, the machine comprises a bed 15 having formed on its upper surface spaced ways 16 and 17 respectively supporting a wheel head indicated generally by the reference character 18 and a work head likewise indicated generally by the reference character 19. The wheel head and work head are each adapted to be shifted relative to the ways 16 and 17 for operatively associating the work and grinding wheel and for breaking up grinding lines and the like on the work and for producing the desired finish thereon.

The wheel head 18 comprises a slide 20 which directly engages the ways 16 and supports thereon a prime mover or electric motor 21. The motor 21 is connected by the usual belt or other transmission inclosed within the housing or guard 22 with a spindle 23 carrying a small diameter or internal grind-

ing wheel 24. The motor 21 is adapted to rotate the grinding wheel 24 at the usual high grinding rate of speed for effecting the stock removal from the work supported by the work head. The slide 20 is secured in any desirable manner to the forward end of a piston rod 25, see Figure 11, which extends from a piston 26 inclosed in a cylinder 27 supported by the bed interiorly thereof. A spool valve 28 mounted in a valve casing 29 is employed for directing the hydraulic pressure to opposite ends of the cylinder 27. This valve 28 has extending from it a suitable stem or connecting member for attaching the valve to the control handle 30 oscillatably mounted at 31 on the forward face of the bed 15. A valve 28 is adapted to be automatically reversed at each end of the stroke of the slide 20 for which purpose it is provided on its forward face with a T-slot 32 whereby dogs 33 and 34 are adjustably secured to the slide. The operating portions of the dogs 33 and 34 have disposed between them the free end of the lever 30 and are adapted to engage the said lever for shifting same for correspondingly shifting the valve 28.

The work head 19 includes a main slide 35 which directly engages with the table guideways 17 and has projecting from its upper surface a dove-tailed guide or tongue 36 received in a correspondingly shaped guideway 37 formed in the lower surface of a cross slide 38. This slide 38 in turn supports an oscillatable or rotary slide 39 on which the work is mounted as will later appear. The slide 39 has rising from it a housing 40 which supports on the upper surface thereof a prime mover or motor 41 geared through suitable transmission inclosed within the guard 42 and housing 40 with a spindle 43, see Figure 3, rotatably journaled in suitable bearings provided by the housing 40. The spindle 43 has secured to it for movement therewith the friction drive or work rotation control wheel 44 which is employed for effecting the rotation of the work while being operated upon.

Mounted on the swivel slide 39 is a supplementary slide 45. This slide 45 is provided near its inner end with ears or lugs 46 forming bearings for a shaft 47 on which is oscillatably journaled a cradle or swinging bracket 48. The bracket 48 terminates in a ball socket 49 receiving the ball end 50 of an arm or bracket 51. A cap 52 is mounted on the cradle 48 and clamps the ball 50 in any of its adjusted positions. The arm or bracket 51 has journaled in its free end a shaft or spindle 53 to which is secured a disk or roller 54 which in actual practice is opposed to the regulating or friction drive wheel 44 and between the proximate points of said disk or pressure roll 54 and regulating wheel 44 is formed the grinding throat. The disk or roller 54 is further adjusted through its ball and socket connection 50 to dispose its axis

at an angle to the axis of the friction drive or regulating wheel thereby exerting a feed component or thrust on the work in a rearward direction for a purpose that will later be described.

Mounted on the swivel slide 39 in between the friction drive or regulating wheel 44 and the disk or pressure roller 54 is an adjustable bracket 55, which, see Figure 3, carries the work rest blade 56. This blade 56 is provided with an inclined upper surface 57 which inclines in a direction toward the operative face of the friction drive or regulating wheel 44 and forms therewith a work receiving trough. The bracket 55 has rising therefrom on the rear surface of the work a plate 58 against which the work is held by the said component or thrust exerted thereon by the pressure roll or disk 54. The bracket 55 has mounted in it near its outer end a spring pressed plunger 59 abutting on its upper end with the cradle or bracket 48 and yieldingly actuating the cradle in a clockwise direction about its pivot shaft 47 into engagement with the work piece 60 mounted on the work rest blade 56 and holding same in operative engagement with the inclined face 57 of the blade and the operative surface of the wheel 44. In other words, a yielding pressure is at all times maintained on the work while being ground to prevent any tilting or lateral movement of the work and insuring same rotating about an axis determined by the finished outer surface thereof.

At the conclusion of the grinding operation the cradle or bracket 48 is oscillated in a counterclockwise direction about the shaft 47 thereby withdrawing the pressure roll or disk 54 from the work whereupon the work is automatically withdrawn from the grinding throat and a new work piece substituted therefor. To this end the cradle 48 has projecting from it a roller 61 adapted to be engaged by a cam 62 having the cam portion 63 formed thereon. The cam 62 is secured to a shaft 64 rotatably mounted in a housing 65 integral with or secured to the supplemental slide 45. The shaft 64 has secured to it within the housing 65 a gear or pinion 66 meshing with the mutilated gear 67. This gear 67 is loosely journaled on a pin or shaft 68 carried by the housing 65 and is further provided with a small mutilated gear 69 meshing with a rack 70. The large mutilated gear 67 also meshes with a gear or pinion 71 secured to a shaft 72 journaled in the housing 65 and having secured to it at a point outside the housing an ejector arm 73 adapted to engage the work at the conclusion of the grinding operation and withdraw it from the machine.

The mutilated gear 67—69 is operated by the rack 70 which is secured to or formed integral with a piston 74 inclosed within a cylinder 75 formed in the supplemental bracket 45. The cylinder 75 is closed at one end by means

of a cap or head 76 carrying an adjustable abutment screw 77. The other end of the cylinder 75 is also closed by a cap or head 78 in which is adjustably mounted a plug 79 having the shoulder 80 formed thereon and forming an abutment for the piston 74 to limit its movement to the right, as seen in Figure 3. The plug 79 has projecting from it a circular tubular sleeve 81 which is encircled by the adjacent end of the piston 74. The piston 74 is further formed interiorly thereof and at the end of the tubular sleeve with a chamber 82. The plug 79 is provided through the sleeve 81 with cross ports 83 and with additional cross ports 84 at a point within the cap or head 78. The head 78 is further provided with a port 85 communicating with the ports 84. The port 85 in the head 78 is controlled by an adjustable choke or needle valve 86. A main port 87 is formed in the slide 45 which terminates in the end of the cylinder adjacent the cap or head 78. The slide 45 is further provided with a main port 88 which terminates in the cylinder at the end adjacent the cap or head 76.

After the work piece has been reduced to the desired size, the hydraulic pressure is introduced into the cylinder at the end carrying the head 78 for forcing the piston 74 therein to the right, as seen in Figure 3. This movement of the piston 74 oscillates the mutilated gear 67-69 in a counterclockwise direction about the shaft 68 thereby rotating the pinions 66 and 71 in a clockwise direction, as viewed in Figure 3. The movement of these pinions first causes the arm 73 to descend into substantial engagement with the work 60 whereupon the pressure roll or disk 54 is withdrawn from the work through the inter-engagement of the cam 62 and roller 61. At this point the hydraulic pressure is reversed and is directed into the cylinder through the port 88 thereby shifting the piston to the left, as seen in Figure 3, and carrying the work out of the grinding throat and discharging it into the chute or trough 89. The flow of the hydraulic medium is controlled by a suitable valve which will be described in detail later.

It is desired that the ejector arm approach the work at a rapid rate and that it carry the work from the machine and discharge it into the chute 89 at a slower rate. For this reason the pressure has an unobstructed flow through the port 87 into the cylinder 75 and an unobstructed flow from the other end of the cylinder through the port 88, but when the piston is actuated in the reverse direction, the discharge of the medium into the port 87 is restricted for thereby slowing up the movement of the piston 74 to the left. This is accomplished by trapping some of the hydraulic medium within the recess or chamber 82 and forcing same out through the hollow interior of the sleeve 81, through the cross ports 84, restricted port 85 into

the main conduit 87 when the said piston 74 is moving to the left, as in Figure 3.

For effecting the automatic reverse of the valve controlling the movement of the piston 74 and the subsequent movement of the machine, the shaft 64 has secured to it a pair of cams 90 and 91 each adapted to operate a similar electrical switch 92. The switches are pivoted at 93 to the housing 65 and respectively effect the reverse movement of the valve controlling the movement of the piston 74 and the longitudinal movement of the main wheel head slide 35 as will be described in detail later.

Mounted on the cross slide 38 adjacent the friction drive or regulating wheel 44 is a slide 94 having rising therefrom a bracket or support 95 and terminating in a ledge or shelf 96. An L-shaped bracket 97 having an elongated perforation 98 is mounted on the shelf 96 and has passing therethrough a bolt or the like 99 whereby the bracket 97 is adjustably secured to the shelf 96. The upper end of the bracket 97 has projecting through it a screw 100 having the head 101 thereof received in a T-slot 102 formed in channel member 103 which is carried by the sizing device housing 104. This housing 104 has inclosed therein a lever 105 secured to a shaft 106 oscillatably mounted in the lower end of the housing 104. Secured to the shaft 106 and depending exteriorly of the housing 104 is a finger 107 carrying a diamond sizing point 108 and adapted to be engaged by the operative face of the grinding wheel 24 when the work is reduced to the desired size. Upon reduction of the work to the desired size, the lever 105 is oscillated in a counterclockwise direction for engaging an electrical contact 109 carried thereby with a second electrical contact 110 carried by the housing 104 and completing an electrical circuit for effecting part of the automatic cycle of the machine as will later appear. The arm 105 is held in its circuit making position by a magnetic coil or solenoid 111 which is energized upon completion of the electrical circuit through the contacts 109 and 110.

The cross slide 38 is actuated by hydraulic pressure acting on one end of a piston 112 which has projecting from it, intermediate its ends, a pin 113 received in a slide block 114 mounted between the arms of a fork 115 on the lower end of a lever 116. The lever 116 is keyed or otherwise secured to a shaft 117 supported by a bracket 118 secured to the under surface of the cross slide 38. The bracket 118 is also formed with a cylinder 119 in which is mounted the piston 112. Keyed or otherwise secured to the shaft 117 is a cam 120 having its cam face 121 adapted to engage with a roller 122 carried by a nut 123 threaded on a tubular cross feed screw 124. The screw 123

124 is locked against independent longitudinal movement in the cross slide 38 by means of collars 125 and a shoulder 126 formed thereon. From this it will be seen that as the arm 116 is oscillated, through the shaft 117, it effects corresponding oscillation of the cam 120 thereby moving the nut axially of itself, which carries with it the screw 124 and slide 38. This movement of the cross slide 38 and parts carried thereby effects the feed between the grinding wheel and work to reduce said work to the desired size.

As is well known, grinding wheels are subject to considerable wear and must be periodically trued or resurfaced to maintain the proper grinding face which effects the size thereof which must be compensated for if successive work pieces are reduced to the desired size especially since the cam 120 has but a limited throw. For this reason the piston 112 is provided on the surface opposite to that shown in Figure 9 with a rack adapted to mesh with pinion 127 of a compound gear 128 freely rotatably mounted on a stud 129 carried by the bracket 118. The second gear 130 of the compound gear 128 meshes with a pinion 131 keyed or otherwise secured to a vertical shaft 132 which has on its upper end a bevel gear 133. This gear meshes with a complementary bevel gear 134 splined on a transverse shaft 135 which passes through the hollow interior of the screw 124. The outer end of the shaft 135 has keyed to it a pawl carrier 136 having oscillatably mounted thereon at 137 pawls 138 and 139. The pawls 138 and 139 are respectively adapted to be engaged with fine and coarse ratchets 140 and 141 keyed or otherwise secured to the extending portion of the screw 124. The pawls are spring actuated as by means of springs 142 to engage same with the teeth of the ratchets 140 and 141. The pawls have projecting from them a tail 143 for engagement with lock-out screws 144.

The operation of these parts is as follows: Depending on whether the grinding machine is performing a roughing or a finishing cut one or the other of the pawls 138 or 139 will be locked out by means of the screws 144. In other words, if a roughing operation is being performed then the coarse toothed ratchet will be employed and if a finishing operation, the fine toothed ratchet will be used. The pawl carrier is oscillated in opposite directions each time the piston 112 makes a forward and a reverse stroke or in unison with the oscillations of the feeding cam 120. The parts are so arranged that during the feeding movement between the work and grinding wheel, the pawl is riding idly over the ratchet teeth preparatory to feeding or actuating the said ratchet in a feeding direction during the retracting stroke of the work and wheel. In other words, if the wheel has

been worn or trimmed away to a point where a considerable throw of the cam is necessary, to cause engagement between the wheel and sizing diamond, the pawl will drop behind a tooth on the ratchet and advance it to compensate for the wheel wear.

In the past while the sizing device was adjustable for various sizes of work pieces through the bolts 99 and 100, it was not mounted on a slide such as 94. After the sizing device was so adjusted, it was secured in place and bore a definite relation to the remaining parts of the machine. If work pieces were not held to a definite outside diameter, the holes or bores in said subsequent work pieces varied in accordance with the outside diameter variation because the centers of the bores being ground were variably positioned relative to the sizing point or diamond due to the definite relationship existing between the sizing point or diamond and the operative point of contact of the regulating or friction drive wheel with the outside diameter of the work. Therefore, if the work piece were oversize by even one or two thousandths of an inch, the center of the work was shifted from the sizing point or diamond one-half that amount and when the automatic feed was thrown in, it continued until the grinding wheel engaged the sizing diamond or point, which, however, did not occur until the work was reduced beyond the desired point an amount equal to the oversize of the outside diameter of the work. On the other hand, if the work were undersize, then the center thereof was shifted toward the sizing or diamond point and a lesser amount of grinding resulted than was desired, causing the work piece to have a bore or hole under the desired size and requiring an additional grinding operation to rectify the error. By this invention, the variations in the outside diameter of the work are compensated for so that successive work pieces are reduced to the exact desired size regardless of the circumference size of successive work pieces.

Accordingly the sizing mechanism, as above described, is mounted on a slide such as 94 and has projecting therefrom a rod 145 which passes through a bore 146 formed in the bracket or slide 45. The rod 145 has near its forward end an enlarged bearing 147 which provides a shoulder 148 forming one abutment for a spring 149 encircling the rod 145 and contained within the bore 146. The rear end of this bore 146 is reduced to provide a shoulder 150 which forms the remaining abutment for the spring 149 and due to this construction, the slide 94 is continuously yieldably urged toward the left, as seen in Figure 5. The forward end of the bearing portion 147 is bifurcated and rotatably supports a roller 151 which is held through the spring 149 in contact with the compensating

cam 152. This cam 152 is keyed or otherwise secured to a shaft 153 and adapted to rotate therewith. The cam 152 is provided with two cam surfaces 154 and 155, the former of which is engaged by the roller 151 while the latter is engaged by a second roller 156 rotatably mounted in the end of an arm 157 secured to or formed integral with the cradle or bracket 48.

10 Secured to the other end of the shaft 153 is a mutilated gear or pinion 158 having its teeth 159 in operative engagement with a rack 160 formed integral with or secured to a piston 161. The piston 161 is contained within 15 vertically disposed cylinder 162 closed on one end by a head 163 and on the other end by a head 164 formed integral with a bracket 165. The bracket 165 is secured as by bolts or the like 166 to the cross slide 38.

20 The respective cam surfaces 154 and 155 are of different pitch or of a different cam rise relative to one another or in other words, the rise of the cam surface 155 is such as respects that of the cam surface 154 that the roller 151 is actuated through one half of the distance that the position of the pressure roller 54 varies in its movements between successive work pieces. The cam 152 is further provided with a depression or recess 167 at 30 the end of the cam rise 155 into which the roller 156 drops in order to withdraw the pressure roller or disk 54 from the work.

The cylinder 162 is coupled with the cylinder 75 so that both of the contained pistons are actuated at the same time, but due to the clearance and relationship between the cradle roller 61 and its operating cam 62, the cam 152 is actuated before the cradle is oscillated, thereby bringing the recess 167 of the cam 152 40 in alignment with the roller 156 so that upon engagement between the cam face 63 of the cam 62 with the roller 61 no interference is set up against the oscillation of the said cradle.

In the operation of the compensating cam, 45 a work piece is introduced into the machine and the cradle released by disengaging the cam face 63 and roller 61 whereupon the spring pressed plunger 59 oscillates the said cradle to cause the pressure roller or disk 54 to engage the work and hold the same in contact with the friction drive wheel and work rest blade. The compensating cam 152 is now rotated which has, as above noted, the roller 156 engaging the cam face 155 and the 50 roller 151 engaging the face 154. The oscillation of the cradle about its pivot is controlled by the outside diameter of the work, that is, if successive work pieces vary in size the oscillation of cradle will be more or less and will vary by an amount equal to the difference in said successive work pieces. Now upon rotation of the cam 152 the cam face 155 will contact with the roller 156 at a point which represents the particular size of the 60 work about to be operated upon and as soon

as this point is reached further rotation of the cam will be stopped. During the rotation of this cam its cam face 154 was, through the roller 151, shifting the rod 145 rearwardly and thereby adjusting the slide 94 and sizing mechanism relative to the grinding throat to a point representative of the desired size of the hole to be ground in the particular piece being operated upon. Since the sizing mechanism operates on but one side of the work, or on the radius of the hole, it need only move one-half of the distance that the pressure roll moves, therefore, the difference between the cam faces 154 and 155. From the foregoing, it is believed, that it will be seen there has been provided a mechanism for producing work pieces having the bore therein all to the same size regardless of the condition of the outside of the work piece when mounted in the machine.

The automatic machine diagrammatically shown in Figure 11, operates as follows. The switch contacts 109 and 110 of the sizing mechanism are shown diagrammatically in this figure at 168, which are closed when the work is to the desired size for completing an electrical circuit through the lines 169 and 170 which includes the solenoid 171. The solenoid 171 shifts a valve 172, which directs the hydraulic pressure to one side of the cylinder 119 for retracting the piston 112 therein and stopping further feed between the grinding wheel and work. As diagrammatically illustrated in this figure, a tank or sump 176 is provided containing an hydraulic medium, preferably oil, which is drawn therefrom through pipe or conduit 177 by a pump 178 and forced into the pressure line 179 under working pressure. A branch conduit 180 from the line 179 carries the medium to the valve 172 where it is directed through conduit 181 to the end of the cylinder 119. The hydraulic medium ahead of the piston 112 is discharged through conduit 182 to the valve where it is connected to the branch return line or conduit 183 and the main return or discharge line 184 to the tank 176. Simultaneously with the completion of the electrical circuit 169 and 170, a second electrical circuit including electrical lines 185 and 186 is completed for energizing the solenoid 187 which likewise effects the shifting of a valve 188 for directing the hydraulic medium from the conduit 179 through the branch conduit or line 189 to one end of the work head traversing cylinder 190. This cylinder 190 contains a piston 191 connected by the piston rod 192 to the work head slide for effecting its movement toward and from the grinding wheel for operatively associating and disassociating said wheel and work. The hydraulic medium ahead of the piston 191 is conveyed by conduit 193 to the valve 188 where it is directed to the conduit 194 terminating in the valve casing 195 which 100 105 110 115 120 125 130

contains the valve 196. This valve 196 connects the conduit 194 with either the restricted branch discharge conduit 197 or, and as illustrated, with the branch return conduit 198 which terminates in valve chamber 199. The medium passes from the chamber 199 through a conduit 200 to the branch and main return conduits 183 and 184.

When the slide reaches its rearmost position it closes a switch 201 for completing an electrical circuit through wires or leads 202 and 203 which include a solenoid 204. The solenoid 204 effects the shifting of a valve 205 which connects the hydraulic medium in the pressure line 179 with either of conduits 87 or 88 which, as above noted, terminate at opposite ends of the cylinder 75. Branch conduits 206 and 207 respectively extending from the conduits 87 and 88 terminate at correspondingly opposite ends of the cylinder 162 for actuating the piston 161 therein. As noted above, these pistons respectively shift the ejector arm and cradle and the compensating cam 152. As was above noted, when the piston 74 reaches the end of its stroke in one direction for effecting engagement between the ejector arm and finished work and the retraction of the pressure roller from the work, it through the cam 90 closes one of the switches 92, indicated in Figure 11 by the numeral 92A. The closing of this switch completes an electrical circuit through the lines 208 and 209 which include the solenoid 210. Energization of the solenoid 210 reversely shifts the valve 205 which immediately connects the hydraulic medium with the other ends of the cylinders 75 and 162, causing a retraction of the pistons 74 and 161 for raising the ejector arm 73, permitting a re-engagement between the pressure roller 54 and work and a setting of the sizing mechanism in accordance with the particular diameter of the work now in the grinding throat. When the piston 74 reaches its limit of travel it closes the second of the switches 92 through the cam 91, indicated diagrammatically in Figure 11 by the numeral 92B, which then completes an electrical circuit including the wires 208 and 211 which have in series therewith the solenoid 212. This solenoid reversely shifts valve 188 for connecting the hydraulic medium with the forward end of the piston 191 causing the work head to travel toward the wheel head for operatively associating the work and wheel. When the work head reaches its innermost position, it closes an electrical switch 213 completing an electrical circuit through the wires 214 and 215 thereby energizing the solenoid 216 and reversely shifting the valve 172. This valve 172 then effects or initiates the movement of the piston 112 for feeding the work and wheel relative to one another and effecting a stock removal from the work. As has been noted above, this feed continues

until the grinding wheel 24 engages the sizing diamond or point 108 whereupon the switch 168 is closed for initiating the automatic cycle of the machine as above outlined.

As further illustrated, diagrammatically in Figure 11 and structurally in Figure 3, to retrue or redress the active face of the grinding wheel, there is provided a piston cylinder 217 which is formed on the same casting as contains the valve chamber 199. Inclosed within the cylinder 217 is a piston 218 having projecting therefrom a rod 219 bearing a post 220 in which is mounted the truing tool or diamond 221. Connected with the piston 218 is a valve member 222 movable with the piston 218 through the valve chamber 199 for controlling the flow of the hydraulic medium through the said chamber from the conduit 198 to the conduit 200.

The piston 218 is hydraulically shifted by the hydraulic medium under pressure passing through branch conduit 223 to the valve 196 where it is connected with either of conduits 224 and 225 respectively terminating at opposite ends of the cylinder 217. The valve 196 is adapted to be periodically shifted through a lever 226 and solenoids 227 and 228. The former is included in the electrical circuit 229 and 230 which is interruptable by a switch 231 mounted on the rear surface of the bed 15. The switch is closed by a dog 232 secured to the rear surface of the work head slide 35. Substantially at the same time of closing of the switch 231 by the work head slide a second switch, 233, also mounted on the rear surface of the bed 15, is closed by means of a dog 234 carried by the wheel head slide which completes an electrical circuit 235 and 236. The closing of this circuit energizes a solenoid 237 shifting a stop valve 238 for stopping the wheel head. After the wheel has been retrued a second dog 239 carried by the work head slide 35 closes a switch 240 completing an electrical circuit 241 and 242 for energizing solenoids 228 and 243 for reversely shifting the valves 196 and 238 for returning the parts to their normal operating position.

From the foregoing, it will be noted that there has been provided an automatic grinding machine in which the work pieces are held to an absolute predetermined size and in which the sizing mechanism is automatically adjusted for compensating for variance in other controlling factors such as the outside diameter of the work.

What is claimed is:

1. In a grinding machine of the class described the combination of a bed, a work support on the bed, a grinding wheel on the bed, means for effecting a relative feed between the grinding wheel and work, a sizing device for engagement with the wheel for automatically stopping the relative feed between the work and wheel when the work is

reduced to the desired size, and means for automatically adjusting the position of the sizing device relative to the work and wheel in accordance with the size of the work being ground.

2. In an internal grinding machine for grinding the hole or bore of a work piece concentric with the outside finished diameter thereof, the combination of means for supporting the work on said outside finished peripheral surface, a grinding wheel, a feeding mechanism for effecting a relative feed between the work and wheel, means operable when the work is to the desired size for stopping further feed between the work and wheel, and means for adjusting the position of the sizing devices in accordance with the outside diameter of the particular piece of work being operated upon whereupon successive work pieces are produced having the same size bore.

3. In an internal grinding machine of the class described the combination of a work support peripherally supporting the work on its exterior diameter, a grinding wheel for grinding a bore in the work concentric with the said exterior diameter, a feeding mechanism for effecting relative movement between the grinding wheel and work, means for holding the work on its support and for contacting with said work, a sizing device for engagement with the grinding wheel to suspend further feed between the work and wheel, and means operated through the movement of the work contacting member for adjusting the position of the sizing device relative to the grinding wheel.

4. In an internal grinder of the class described the combination of a bed, a work head mounted thereon for movement relative thereto, a wheel head mounted on the bed for movement relative thereto, a work support on the work head, a grinding wheel on the wheel head, automatic means for cyclically shifting the work head and wheel head toward and from one another, a pressure roll for yieldably holding the work on the work support, an oscillatable carrier for the pressure roll, a sizing mechanism carried by the work head for engagement with the grinding wheel at the conclusion of the grinding operation and effecting the relative retraction of the wheel head and work head, and means controlled by the pressure roll oscillatable carrier for adjusting the position of the sizing mechanism relative to the wheel and work for thereby insuring successive work pieces having the same size bore therein.

5. In an internal grinder of the class described the combination of a bed, a work head mounted thereon for movement relative thereto, a wheel head mounted on the bed for movement relative thereto, a work support on the work head, a grinding wheel on the wheel head, automatic means for cyclically shifting

the work head and wheel head toward and from one another, a pressure roll for yieldably holding the work on the work support, an oscillatable carrier for the pressure roll, a sizing mechanism carried by the work head for engagement with the grinding wheel at the conclusion of the grinding operation and effecting the relative retraction of the wheel head and work head, and means controlled by the pressure roll oscillatable carrier for adjusting the position of the sizing mechanism relative to the wheel and work for thereby insuring successive work pieces having the same size bore therein, said means including a cam having a cam face for engagement with the pressure roll bracket and having a second cam face for engagement with the sizing mechanism and shifting same thereby.

6. In an internal grinder of the class described the combination of a bed, a work head mounted thereon for movement relative thereto, a wheel head mounted on the bed for movement relative thereto, a work support on the work head, a grinding wheel on the wheel head, automatic means for cyclically shifting the work head and wheel head toward and from one another, a pressure roll for yieldably holding the work on the work support, an oscillatable carrier for the pressure roll, a sizing mechanism carried by the work head for engagement with the grinding wheel at the conclusion of the grinding operation and effecting the relative retraction of the work head and wheel head, means controlled by the pressure roll oscillatable carrier for adjusting the position of the sizing mechanism relative to the wheel and work for thereby insuring successive work pieces having the same size bore therein, said means including a cam having a cam face for engagement with the pressure roll bracket and having a second cam face for engagement with the sizing mechanism and shifting same thereby, and yielding means for maintaining contact between the sizing device and its cam face.

7. In a device of the class described the combination of a work support, a friction drive wheel on one side of the work support and contacting with a work piece on the support, a pressure roll on the other side of the work support for engagement with the work, a bracket pivotally supporting the pressure roll for oscillatory movement toward and from the work, yielding means for holding said pressure roll against the work for holding same in contact with the work support and friction drive wheel, a cam having a pair of cam surfaces thereon, means supporting the cam for oscillatory movement and with one cam face engaging with the pressure roll bracket, a grinding wheel for operation on the bore of the work, means for effecting a relative feed between the grinding wheel and work, a sizing mechanism for interrupting said feed, and means connecting the sizing

- mechanism with the second cam face for adjusting said sizing mechanism an amount to properly position the sizing device relative to the grinding wheel and determined by the movement of the pressure roll bracket toward the work to effect engagement between the roll and work.
8. In a sizing mechanism of the class described the combination of a work support adapted to peripherally engage the work during operation thereon, a friction drive wheel on one side of the work support for engaging the work and controlling its rotation, a pressure roll on the other side of the work support for engaging the work and holding same in contact with the support and friction drive wheel, yielding means for oscillating the pressure roll toward the work, hydraulically actuatable means for retracting the pressure roll against its yielding means, a grinding wheel for operation on the work, means for effecting a relative feed between the wheel and work, a sizing mechanism for interrupting said feed, means supporting the sizing mechanism for movement relative to the work toward and from the grinding wheel, yielding means for urging the sizing mechanism in one direction, positive means for shifting the sizing mechanism in the other direction, and an operative coupling between the pressure roll and sizing mechanism whereby they are simultaneously shifted relative to the work for respectively holding the work in the grinding throat and positioning the sizing device in accordance with the particular size of the work on the support.
9. In a sizing mechanism of the class described the combination of a work support adapted to peripherally engage the work during operation thereon, a friction drive wheel on one side of the work support for engaging the work and controlling its rotation, a pressure roll on the other side of the work support for engaging the work and holding same in contact with the support and friction drive wheel, yielding means for oscillating the pressure roll toward the work, hydraulically actuatable means for retracting the pressure roll against its yielding means, a grinding wheel for operation on the work, means for effecting a relative feed between the wheel and work, a sizing mechanism for interrupting said feed, means supporting the sizing mechanism for movement relative to the work toward and from the grinding wheel, yielding means for urging the sizing mechanism in one direction, positive means for shifting the sizing mechanism in the other direction, an operative coupling between the pressure roll and sizing mechanism whereby they are simultaneously shifted relative to the work for respectively holding the work in the grinding throat and positioning the sizing device in accordance with the particular size of the work on the support, said means comprising a cam having a pair of cam faces thereon, one of said cam faces adapted to contact with the pressure roll, the other of said cam faces adapted to contact with the sizing mechanism, and hydraulically actuated means for rotating said cam and shifting said sizing device.
10. In a sizing mechanism of the class described the combination of a work support adapted to peripherally engage the work during operation thereon, a friction drive wheel on one side of the work support for engaging the work and controlling its rotation, a pressure roll on the other side of the work support for engaging the work and holding same in contact with the support and friction drive wheel, yielding means for oscillating the pressure roll toward the work, hydraulically actuatable means for retracting the pressure roll against its yielding means, a grinding wheel for operation on the work, means for effecting a relative feed between the wheel and work, a sizing mechanism for interrupting said feed, means supporting the sizing mechanism for movement relative to the work toward and from the grinding wheel, yielding means for urging the sizing mechanism in one direction, positive means for shifting the sizing mechanism in the other direction, an operative coupling between the pressure roll and sizing mechanism whereby they are simultaneously shifted relative to the work for respectively holding the work in the grinding throat and positioning the sizing device in accordance with the particular size of the work on the support, said means comprising a cam having a pair of cam faces thereon, one of said cam faces adapted to contact with the pressure roll, the other of said cam faces adapted to contact with the sizing mechanism, hydraulically actuated means for rotating said cam and shifting said sizing device, and means for connecting the hydraulic mechanisms of the pressure roll retracting means and cam rotating means to insure timed sequential movement thereof.
11. In a mechanism for interrupting the feed between a work piece and grinding wheel when the hole therein is reduced to the desired size the combination with a work receiving throat comprising opposed friction drive wheel and pressure roll forming the throat and having a work rest blade therein, of means for supporting one of these parts for oscillatory movement toward and from the remaining parts and together constituting a caliper for measuring the work within the throat, a feeding mechanism for actuating the grinding wheel and the work relative to one another, a sizing mechanism for interrupting this feed, and means for adjusting the position of the sizing mechanism relative to the throat to position same in accordance with the size of the work.

with the size of the work as determined by the caliper members.

12. In a mechanism for interrupting the feed between a work piece and grinding wheel when the hole therein is reduced to the desired size the combination with a work receiving throat comprising opposed friction drive wheel and pressure roll forming the throat and having a work rest blade therein, of means for supporting one of these parts for oscillatory movement toward and from the remaining parts and together constituting a caliper for measuring the work within the throat, a feeding mechanism for actuating the grinding wheel and the work relative to one another, a sizing mechanism for interrupting this feed, means for adjusting the position of the sizing mechanism relative to the throat to position same in accordance with the size of the work as determined by the caliper members, said means comprising a cam having a pair of cam faces thereon and which bear a varying rising relationship to one another, the larger cam rise face being adapted to contact with the shiftable caliper member, while the remaining face is adapted to engage the sizing mechanism, and means for rotating the cam after the work piece is within the throat, which rotation is stopped by engagement of the cam face with the caliper member.

13. In a mechanism for interrupting the feed between a work piece and grinding wheel when the hole therein is reduced to the desired size the combination with a work receiving throat comprising opposed friction drive wheel and pressure roll forming the throat and having a work rest blade therein, of means for supporting one of these parts for oscillatory movement toward and from the remaining parts and together constituting a caliper for measuring the work within the throat, a feeding mechanism for actuating the grinding wheel and the work relative to one another, a sizing mechanism for interrupting this feed, means for adjusting the position of the sizing mechanism relative to the throat to position same in accordance with the size of the work as determined by the caliper members, said means comprising a cam having a pair of cam faces thereon and which bear a varying rising relationship to one another, the larger cam rise face being adapted to contact with the shiftable caliper member, while the remaining face is adapted to engage the sizing mechanism, means for rotating the cam after the work piece is within the throat, which rotation is stopped by engagement of the cam face with the caliper member, the varying ratio between the cam faces effects a shifting of the sizing mechanism one-half of the distance that the throat member moves and thereby insures the proper positioning of the sizing mechanism relative to the wheel and work regardless of the outside diameter of the work, and yielding means for maintaining contact between the sizing mechanism and its cam face.

wheel and work regardless of the outside diameter of the work.

14. In a mechanism for interrupting the feed between a work piece and grinding wheel when the hole therein is reduced to the desired size the combination with a work receiving throat comprising opposed friction drive wheel and pressure roll forming the throat and having a work rest blade therein, of means for supporting one of these parts for oscillatory movement toward and from the remaining parts and together constituting a caliper for measuring the work within the throat, a feeding mechanism for actuating the grinding wheel and the work relative to one another, a sizing mechanism for interrupting this feed, means for adjusting the position of the sizing mechanism relative to the throat to position same in accordance with the size of the work as determined by the caliper members, said means comprising a cam having a pair of cam faces thereon and which bear a varying rising relationship to one another, the larger cam rise face being adapted to contact with the shiftable caliper member, while the remaining face is adapted to engage the sizing mechanism, means for rotating the cam after the work piece is within the throat, which rotation is stopped by engagement of the cam face with the caliper member, the varying ratio between the cam faces effects a shifting of the sizing device one-half of the distance that the throat member moves and thereby insures the proper positioning of the sizing mechanism relative to the wheel and work regardless of the outside diameter of the work, and yielding means for maintaining contact between the sizing mechanism and its cam face.

In testimony whereof, I affix my signature.
LESTER F. NENNIGER.
